UNITED STATES PATENT OFFICE.

JESSE PRUETT JACOBS, OF SHELBYVILLE, TENNESSEE.

WHEEL FOR AUTOMOBILES.

1,420,195.

Specification of Letters Patent. Patented June 20, 1922.

Application filed May 7, 1921. Serial No. 467,631.

To all whom it may concern:

Be it known that I, JESSE PRUETT JACOBS, a citizen of the United States, and a resident of Shelbyville, in the county of Bedford and State of Tennessee, have invented certain new and useful Improvements in Wheels for Automobiles, of which the following is a specification.

The present invention relates in general to wheels for automobiles or the like, and more particularly to a demountable rim therefor.

The object of the invention is to provide a demountable rim of this character which is of extremely simple and durable construction, reliable in operation and easy and inexpensive to manufacture; which may be easily assembled with and disassembled from the wheel; which is automatically locked in assembled position and which when assembled is positively secured against and effective to withstand lateral as well as radial thrust.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a fragmentary view in side elevation, parts being broken away for the sake of illustration;

Figure 2 is a transverse sectional view, on line 2—2 of Figure 1; and

Figure 3 is a transverse sectional view on line 3—3 of Figure 1.

Referring to the drawings wherein for the sake of illustration is shown the preferred embodiment of the invention, the numeral 10 designates generally a wheel or the like which includes as usual a hub 11, spokes 12 and a felly 13. The felly in the present invention however is of a special construction, being preferably constituted by an annular channel of steel or the like, as clearly shown in Figures 2 and 3. The channel includes as usual a base 14 and side flanges 15.

Rollers designated generally at 16, are mounted on the channel constituting the felly at regular intervals about the circumference thereof. These rollers are preferably of spool-like form having a central hub or body portion 17 and heads 18 at each

end of the body portion provided with inwardly-inclined or tapered surfaces 19 and having at their ends trunnions 20 rotatably received in suitable journals provided therefor in the side flanges 15 of the felly. The lateral faces of the heads 19 from which the trunnions 20 project are smooth so that the rollers are readily rotated on their trunnions 20.

A demountable rim, designated at 21, is mounted on the felly and is provided at spaced intervals around its inner periphery or circumference with inwardly extending lugs 22, there being one of such lugs for each roller 16 provided on the felly. These lugs 22 have their inner surface 23 inclined and these surfaces are all inclined in the same direction. The lateral faces of the lugs are also inclined, as designated at 24, correspondingly with the inclination of the faces 19 of the rollers. As shown in the drawings, the faces 23 of the lugs bear upon the body portion or hub 17 of the rollers and the lateral faces 24 of the lugs bear upon the inclined faces 19 of the heads of the rollers. In order to permit assembly of the demountable rim upon the felly one of the side flanges is provided with a plurality of notches designated at 25, adjacent each roller, as shown in Figure 1. As shown in Figures 2 and 3, the other side flange 15 of the felly is provided with an extension 26 upon which the inner side of the rim bears.

Means is provided for imparting relative rotary motion to the demountable rim with respect to the felly and includes a segmental ring gear 27 fixed to the under side of the rim and adapted to be meshed with a driving pinion 28 journaled in the side flanges of the felly and having a squared extension 30 on the shaft adapted to be engaged with an operating tool or the like. A spring pressed plunger 31 is arranged in the felly and is adapted to be engaged with the ring gear 27 to lock the ring gear in adjusted position. The spring pressed plunger is provided with a hand grip 32 whereby it may be withdrawn against the action of the spring to permit disassembly of the rim.

In practice, the demountable rim may be easily assembled and disassembled as in assembling it is only necessary to align the notches 25 with the lock lugs 22 and then move the rim laterally until it is on the

elly. When it is well on the felly a suitable operating tool is engaged with the squared extension 30 to rotate the pinion 28 and thus impart desired rotation to the rim. This causes the lock lugs to ride up upon the rollers 17 and at this time the under face 23 of the lock lugs is supported upon the body portion or hub 17 of the rollers and the lateral faces 24 of the lock lugs bear upon the inclined faces 19 of the heads of the rollers and thus the rim is securely mounted upon the felly and is capable of withstanding lateral as well as radial thrust while at the same time being susceptible of easy assembly and disassembly. When the rim has been adjusted to desired position, the spring pressed plunger 31 engages the ring gear securing it in position.

I claim:

1. In a device of the character described, a wheel having a felly of channel form including a base and side flanges, a plurality of spaced rollers carried by said felly including a hub, heads at the ends of said hub having inclined faces adjacent said hub, and trunnions carried by said heads and rotatably journaled in the side flanges of said felly, a demountable rim having a plurality of lugs having inclined under faces engageable with the hubs of the rollers and inclined lateral faces engageable with the inclined faces of the heads of said rollers, said felly having notches adjacent said rollers to permit passage of said lock lugs, means for rotating said rim relative to said felly, including a ring gear and a pinion carried by said felly and engaged with said ring gear, and a spring pressed plunger carried by said felly and engageable with the teeth of said ring gear.
2. In a device of the character described, a wheel having a felly of channel form including a base and side flanges, a plurality of spaced rollers carried by said felly including a hub, heads at the ends of said hub having inclined faces adjacent said hub and trunnions carried by said heads and rotatably journaled in the side flanges of said felly, a demountable rim having a plurality of lugs having inclined under faces engageable with the hubs of the rollers and inclined lateral faces engageable with the inclined faces of the heads of said rollers, said felly having notches adjacent said rollers to

permit passage of said lock lugs, and means for rotating said rim relative to said felly.

3. In a device of the character described, a wheel having a felly of channel form including a base and side flanges, a plurality of spaced rollers carried by said felly including a hub, heads at the ends of said hub having inclined faces adjacent said hub, and trunnions carried by said heads and rotatably journaled in the side flanges of said felly, and a demountable rim having a plurality of lugs having inclined under faces engageable with the hubs of the rollers and inclined lateral faces engageable with the inclined faces of the heads of said rollers, said felly having notches adjacent said rollers to permit passage of said lock lugs.

4. A demountable rim of the character described comprising a plurality of rollers adapted to be carried by the felly of the wheel and each including a hub and heads at the ends of the hub having inclined surfaces adjacent said hub and lock lugs carried by the under side of the rim and having inclined under faces engageable with the heads of the rollers and inclined lateral faces engageable with the inclined surfaces of the head of the rollers.

5. A demountable rim of the character described, comprising rollers adapted to be carried by the felly and lock lugs adapted to be carried by the rim and engageable with said rollers.

6. In combination, a felly, a plurality of rollers journaled on said felly, a demountable rim, lugs carried by the under side of said rim and engageable with said rollers, and means for imparting relative rotary means to said demountable rim.

7. In combination, a felly of channel form, a plurality of rollers journaled on said felly, a demountable rim, lugs carried by the under side of said rim and engageable with said rollers, means for imparting relative rotary means to said demountable rim, means for locking said rim and said felly in assembled position.

8. In combination, a felly, a plurality of rollers journaled on said felly, a demountable rim, lugs carried by the underside of said rim and engageable with said rollers; and means for locking said rim and said felly in adjustable position.

JESSE PRUETT JACOBS.
